ILLUMINABLE LAWN SPRINKLER

Robert L. Litchfield, Harper Woods, Mich.

Application May 24, 1956, Serial No. 41,636

Term of patent 14 years

(Cl. D91—1)

FIG. 1

FIG. 2

FIG. 3

Fig. 1 is a perspective view of an illuminable lawn sprinkler showing my new design with a section of the cable shown broken away in part for convenience of illustration;

Fig. 2 is a top plan view of Fig. 1; and

Fig. 3 is a front elevational view of Fig. 1.

The cable is shown broken away in Figs. 2 and 3 for convenience of illustration only.

The dominant features of my design reside in the portion shown in full lines.

I claim:

The ornamental design for an illuminable lawn sprinkler, substantially as shown and described.
